UNITED STATES PATENT OFFICE.

WILLIAM E. STORY, JR., OF WASHINGTON, DISTRICT OF COLUMBIA, ASSIGNOR TO
GENERAL ELECTRIC COMPANY, A CORPORATION OF NEW YORK.

HIGH-PRESSURE ARC.

Application filed July 5, 1922. Serial No. 572,945.

To all whom it may concern:

Be it known that I, WILLIAM E. STORY, Jr., a citizen of the United States, residing at Washington, District of Columbia, have 5 invented certain new and useful Improvements in High-Pressure Arcs, of which the following is a specification.

My invention relates to light projecting equipment in which an arc-light is used, 10 the arc being maintained in a chamber containing gas above atmospheric pressure. This invention is especially adapted for use in connection with moving picture projectors, spotlights and the like.

It is well known that the intrinsic brilliancy of the arc increases with the pressure of the medium in which it is maintained. Heretofore efforts have been made 15 to produce a practical equipment embodying an arc-light under pressure but inasmuch as the arc has to be set up within an opaque pressure chamber of steel or the like, a window with a pane of glass or other transparent material has to be provided 20 through which the light passes to the screen or other point where the light is wanted. In such equipment of the prior art the condenser lens is outside the pressure chamber and therefore to obtain a maximum brilliancy at the point wanted the arc must be 25 brought as near the window as possible. When this is done the window becomes excessively hot due to the combined effect of 30 radiation, conduction and convection and as a result there is an increased liability of the window glass cracking. Furthermore, the 35 nearer the arc is brought to the window, the greater the liability of condensation or deposit on the glass of the by-products of the 40 arc. There is another form of construction that has been heretofore employed to enable the arc to be set further back from the window. In this construction a larger window is employed with the framework having 45 a number of small openings each of which is covered or sealed with a window pane, each pane being small enough to withstand the pressure, but this construction is 50 objectionable for the reason that the framework of the window cuts off a large percent of the light. It is one of the objects of 55 my invention to provide means within the pressure chamber for collecting the diverging rays of the arc and sending as many through the small window arrange-

ment with the arc set back as with the arc close up to the window with the lens on the outside. With this arrangement I avoid the excessive heating of the window pane and reduce to a minimum the liability of 60 having the by-products of the arc deposit on the window which deposit of course reduces the amount of light transmitted.

In order to further minimize the liability 65 of such deposit and to keep the chamber cooler than otherwise would be the case, I also propose to provide means for causing a circulation of the gas in the pressure chamber to take place, the direction of the circulation being away from the window and 70 away from the lens and toward an exit located in the rear of the pressure chamber. This arrangement will enable the by-products of the arc to be carried off at the same time that the result of cooling is obtained. 75

I also contemplate other details of improvement which will more fully appear from the following specification wherein all means which I propose to employ are more 80 fully set forth and claimed, reference being had to the accompanying drawing. In the said drawing the figure shows the pressure chamber in sectional elevation and it also shows apparatus by means of which a circulation of the gas is produced and maintained. 85

Referring more in particular to the said drawing, the housing 2 contains the pressure chamber 3 in which the arc-lamp is located and in which the electrodes 4 and 5 of the arc-light are also located. It will be understood of course that suitable electrical connections are provided between the electrodes and suitable terminals on the outside 90 of the pressure chamber which need not be described. To the left of the arc and within the chamber I show the condenser lens 6 which will collect the rays from the arc and send them through the window 7 as effectively as though the arc were as close to the 95 window as it is to the lens. The condenser lens will be heated by the arc but inasmuch as the lens is inside the chamber the distribution of the heat is more uniform which of course makes it safer. In other words, 100 there is less liability of cracking the lens by bringing it close to the arc inside of the chamber than there is of cracking the window by bringing the arc close to the window. In connection with this pressure 105 110

chamber, I provide a gas reservoir 8 containing gas at higher pressure than the pressure maintained in the chamber 3. From this reservoir pipe lines 9 are provided 5 which supply gas to the chamber 3. The gas is forced through the chamber and out of the valve 10 shown near the upper right hand portion of the chamber, thus producing a circulation which keeps down the temperature and at the same time drives out through the valve the by-products of the arc as heretofore pointed out. Therefore the by-products are prevented from depositing in the chamber and particularly on the 10 lens window. It will be understood that the valve 10 may be of any suitable construction; an ordinary safety valve, for example, will serve the purpose. Just at the point where the pipes 9 terminate at the housing 15 2 I provide check valves 11 which also may be of any suitable construction that will permit gas to go into the chamber 3, but which will prevent flow in the reverse direction; that is, from the chamber into the 20 pipes 9. Between the reservoir 8 and the valves 11 I provide a shut off valve 12 for regulating the rate of flow into the chamber 3 from the reservoir. To the right of the reservoir I have shown a pump 13 which

may be of any suitable construction for 30 maintaining a constant pressure in the reservoir 8. Therefore by the use of such simple and effective means as described, I am enabled to accomplish the results heretofore pointed out and to avoid the objections to 35 which I have referred.

What I claim as new and desire to secure by Letters Patent of the United States, is:—

A light projector comprising a sealed chamber, a transparent window in the wall 40 of said chamber, an arc lamp within said chamber, a condensing lens located between the arc and the window for collecting rays of light from the arc and directing them through the window, an inlet valve together with an outlet valve for said chamber, means for supplying gas under pressure to operate the intake valve whereby gas may be forced into the chamber so that the arc 45 may be operated under pressure to increase its brilliance and whereby the outlet valve may be operated when a predetermined pressure is obtained for maintaining the pressure in the chamber constant and for producing circulation within the chamber. 50

In witness whereof, I have hereunto set my hand this 5th day of July, 1922.

WILLIAM E. STORY, JR.
